UNITED STATES PATENT OFFICE

EDWARD W. ANDEREGG, OF ALGOMA, WISCONSIN

FOLDING COMBINATION BATHTUB AND DRESSING TABLE

Application filed May 16, 1931. Serial No. 537,927.

- This invention relates to combination bathtubs and dressing tables, and more particularly to a device of this kind which is adapted for use in the bathing of babies.
- 5 An object of this invention is to provide a combined tub of foldable construction which, when folded, will occupy a relatively small space, the tub being disposed at a convenient height.
- 10 Another object of this invention is to provide in a construction of this kind means for providing a dressing table upon which the baby may be disposed when dressing the baby, the table construction being carried by 15 the foldable tub construction and movable into operative or inoperative position so that when it is in inoperative position, the table will not interfere with the normal use of the tub.
- 20 A further object of this invention is to provide a flexible table construction which is mounted on a frame, the flexible top of the table being stretched within the frame and being of a strength to support a child 25 thereupon.
- A still further object of this invention is to provide in a construction of this kind means for supporting articles used in the bathing and dressing of babies, the articles 30 being supported at a convenient location where they may be used during the time that the device is used as a tub or during the time that the device is used as a dressing table.
- The above and various other objects and 35 advantages of this invention will in part be described in and in part be understood from the following detailed description of the present preferred embodiment, the same being illustrated in the accompanying drawings, wherein:—
- Figure 1 is a detail perspective view of a device constructed according to the preferred embodiment of this invention;
- Figure 2 is a fragmentary perspective view 45 of the table;
- Figure 3 is a fragmentary perspective view showing the table in inoperative position, and
- Figure 4 is a fragmentary detail perspective view of the rear edge of the table.
- Referring to the drawings wherein like numerals of reference designate corresponding parts throughout the several views, the numeral 10 designates generally a foldable frame structure upon which a flexible tub construction 11 is mounted. The frame structure 10 comprises end members 12 which are pivotally secured together intermediate their ends by means of pivotal members 13 and bracing members 14 connect opposite end members together for simultaneous movement. A top connecting bar 15 also connects opposing end members 12.
- At the front edge of the frame structure 10, there is provided an elongated flexible sheet 16 which has the lower end thereof free and is provided with pocket members 17 at each end thereof and an intermediate pocket 18, this intermediate pocket 18 having a rubber or water-proof lining 19 so that wet articles may be disposed therein without dripping downwardly onto the floor. These pockets 17 are adapted to receive articles in the form of clothing or the like, and the intermediate pocket 18 is adapted to receive wash rags, soap or the like used in the bathing of the child positioned within the tub 11.
- When the frame structure 10 is in unfolded or operative position, the article holding member 16 will be disposed in depending or vertical position and when the frame 10 is in collapsed or folded position, the article holding member 16 will lie flat against the frame structure and the tub 11. The tub 11 is provided with a draining outlet 20 and a valve 21 is interposed in a pipe or tube 22 which is connected to the outlet 20. In this manner, the water within the tub 11 may be readily drained outwardly therefrom through the bottom of the tub.
- A second article holding member or rack 23 is mounted on a frame structure generally designated as 24, which comprises a U-shaped bar 25 having a connecting member 26 connected to the opposite legs thereof intermediate the ends of the legs, and the free ends of the legs of the U-member 25 are offset, as at 27, and removably engage in apertures 28 provided in the rear bar 15' of the frame structure 10. A flexible sheet 29 is

disposed within the frame structure 24 and is provided with a plurality of pockets 30 which open upwardly and which are adapted to receive articles used in the bathing and dressing of the child.

- 5 A dressing table structure, generally designated as 31, is slidably mounted on the upper portion of the frame structure 10, this dressing table 31 being constructed of a single length of wire which is formed in substantially rectangular configuration, and a flexible table top or supporting member 32 is stretched within the wire frame, the marginal edges of the table top 32 being folded 10 or looped over the wire frame and sewed to the top 32 by means of stitching or the like. This wire frame comprises a forward or front bar 33, a rear bar 34 and end bars 35, all of which are integrally formed with each 15 other. This front bar 33 is provided at substantially the center thereof with an offset loop or handle structure 36 and the rear bar 34 is provided at substantially the center thereof with a loop 37 which constitutes a stop 20 member, the purpose for which will be hereinafter described.

At the junction between the front and rear bars 33 and 34, respectively with the end bars 35, there is provided a downwardly and upwardly offset leg 38 of substantially L-shaped construction, one portion of the member 38 being disposed at substantially right angles to the front and side members, and the opposite leg being disposed in parallel relation 35 thereto.

By forming the wire frame as hereinbefore described, the end members 35 are adapted to be disposed between the offset portions 27 of the rear rack 23 and when the device is 40 used for bathing the child, the table structure 31 is positioned in inoperative position at the rear of the frame 10, being held in substantially vertically disposed and depending position by means of the offset portions 38 at the 45 forward edge of the wire frame and by means of the offset handle 36.

When it is desired to use the table structure 31, the handle 36 may be grasped and the table structure lifted upwardly to the 50 limit permitted by the stop 27 and the rear end members 38. When the table structure 31 is resting on the upper braces 15 and 15' of the frame 10, the handle 36, together with the forward offset members 38, will cooperate 55 with the rear stop member 37 and the rear offset leg members 38 in preventing lateral movement of the table structure on the frame 10. Longitudinal movement of the table structure 31 is prevented by means of the offset 60 set portions 27 of the article rack 23.

In order to prevent a child or the like from rolling off of the table 31, I have provided a flexible securing member 39 which is provided with spaced loops 40 through which the 65 arms of the child are adapted to be projected

and one end of the flexible securing member 39 is secured to the table structure 31, as at 41, while the opposite end is provided with a strap 42 having a buckle 43 attached thereto for engagement with a strap 44 carried by 70 the table structure 31. In this manner, the securing member 39 may be tightened on the chest of the child so as to provide means whereby the child may be prevented from rolling off of the table structure, but at the 75 same time permitted to have the free use of the limbs, and the child may also be partially dressed while secured within the securing structure 39.

It will be obvious, from the foregoing, that 80 a relatively simple and light structure has been disclosed which may be used for a bath tub for bathing an infant, and it may also be used for dressing of the infant.

This combination tub and dressing table 85 may be folded so as to provide an exceedingly small package which will not only facilitate transportation of the device from the manufacturer to the seller and at the same time reduce the cost of freight on the article, 90 but the device will occupy only a relatively small amount of space in a home.

It is, of course, understood that various changes and modifications may be made in the details of construction and design of the 95 above specifically described embodiment of this invention without departing from the spirit thereof, such changes and modifications being restricted only by the scope of the following claim.

I claim:—

In a device as described including a supporting frame, a table member carried by said frame and movable into operative or inoperative position, said member comprising a wire frame, a webbing mounted within the wire frame, said wire frame comprising parallel front and rear members, parallel end members, and L-shaped members carried by the wire frame having one leg thereof disposed at substantially right angles to said front and end members and the other leg disposed in parallel outwardly extended position to said front members, said L-shaped members extending over the supporting frame and maintaining said wire frame against movement in one direction on said supporting frame upon movement of the wire frame into operative position, and holding said wire frame in depending position on said supporting frame when said wire frame is moved into inoperative position.

In testimony whereof I hereunto affix my signature.

EDWARD W. ANDEREGG.
